UNITED STATES PATENT OFFICE.

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN.

DESIGN FOR A LIGHTING-FIXTURE CHANDELIER.

Application filed May 1, 1929. Serial No. 31,063. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Lighting-Fixture Chandelier, of which the following is a specification, reference being had to the accompanying drawing, forming part thereof.

Fig. 1 is a perspective of my chandelier.

Fig. 2 is a view looking upwardly at the structure shown in Fig. 1 showing one of the panels in full outline and the general configuration in dotted outline. It is understood that the ornamentation shown in part is repeated over the entire area.

I claim:

The ornamental design for a lighting fixture chandelier, as described and shown.

GLENN E. McFADDEN.
